UNITED STATES PATENT OFFICE.

GOTTWALT SIEBER, OF PLAUE, GERMANY, ASSIGNOR TO VOGTLÄNDISCHE MASCHINEN-FABRIK, OF PLAUE, GERMANY.

EMBROIDERING-MACHINE.

1,214,599.

Specification of Letters Patent.

Patented Feb. 6, 1917.

Application filed January 19, 1915. Serial No. 3,185.

To all whom it may concern:

Be it known that I, GOTTWALT SIEBER, a subject of the German Emperor, residing at Plauen, in Vogtland, in the Kingdom of 5 Saxony, Germany, have invented certain new and useful Improvements in Embroidering Machines, of which the following is a specification.

The present invention relates to pantograph embroidery machines and has for 10 its object to provide a controlling mechanism whereby much time and labor in the manipulation of large embroidery machines will be saved.

15 Hitherto when the operator of an embroidery machine had to change from ordinary embroidery to say boring, he had to first stop the entire machine, then by turning a hand wheel put it into boring position 20 and move it to and fro in order to draw off sufficient thread from the shuttles and take-ups so that the tambour frame may have the necessary freedom of movement. Such manipulation, particularly with a modern embroidery machine of about 15 yds. length, 25 puts considerable strain on the operator. By my new controlling mechanism this evil is avoided. It is so constructed that the operator needs only to give an impulse to its 30 movement and it will by itself in a positive manner set the needles at rest outside of the fabric, while the take-ups and shuttles continue to move and pull off the length of thread required for the boring operation.

35 Thus if the operator in order, as it often happens, to examine the work, he does not need, as before, to stop the entire machine, but merely has to give an impulse to the controlling mechanism which at once will automatically arrest the needles outside of the 40 fabric and on receiving another impulse against the needles in motion. The operator can adjust the controlling mechanism so that the needles will be automatically stopped 45 after each stitch, to gain time for specially long tambour movements between the individual stitches. He also can so adjust the controlling mechanism that every other stitch is omitted in order to allow of the 50 formation of long stitches. The new controlling mechanism, besides allowing of the needles being stopped in an absolutely positive manner, also has the particular advantage, that it can effect the stopping and 55 starting of the needle motion at any stroke of the machine so that the operator is not bound to wait for a certain stroke to manipulate the needles.

My invention will be more fully understood by reference to the accompanying 60 drawings, in which similar characters denote corresponding parts and in which—

Figure 1 shows in a more or less diagrammatic view an embroidery machine equipped with my new mechanism and Figs. 65 2, 3 and 4 illustrate the operation of the controlling mechanism.

Referring specifically to the drawings 1 denotes the main shaft of the embroidery machine which carries a cam disk 2 serving 70 for the operation of the rows of needles 3, 4. The needle actuating bar 5 carries at its lower end a fixed roller 6 which in coöperation with the cam disk 2 effects the withdrawal of the needles from the fabric indicated by the dotted line 7—7. A second roller 8, which in coöperation with the cam disk 2 moves the needles into the fabric, is borne on a pivot 8' slidably mounted in a slot 9 provided in the bar 5. The pivot 8' 80 of the roller 8 is carried by the free end of a link 10 which together with the link 11 pivoted to the bar 5 forms a toggle mechanism. When the toggle mechanism is collapsed as shown in Fig. 1 the roller 8 occupies a position at the upper end of the slot 9 and is inoperative. When the toggle mechanism 10, 11 is stretched, that is when its links are in a straight line, the bar 5 is 85 lifted whereby the roller 8 is brought to occupy the position at the lower end of the slot 9 and the roller 6 is brought into contact with the cam 2, so that the two rollers 6 and 8 embrace the disk 2 and impart the stitching movement to the needles. Fixed 90 on the shaft 1 of the cam disk 2 is a pinion 15 which through an intermediate gear 16 drives a set of intermeshing gears 17, 18 and 19 twice as large as the pinion 15. Connected to the junction of the two links 10 and 11 of the toggle mechanism is an arm 12 which is pivoted to a lever 13 fulcrumed at 13' and that by a link 14 is connected to an arm of a four-armed lever 20. A second arm 20^a of the lever extends toward one 100 of the faces of the gear 17 provided with concentric grooves 17¹, 17² and is adapted at its end positions to engage one of said grooves and to thus lock the controlling mechanism. A third arm 20^b engages a 110

vertical slide 23 and a fourth arm 20^c engages a loop 37^a formed at one end of a bar 37. The slide 23 has pivoted to its lower end and at opposite sides notched arms 24, 25 which constitute a part of said slide and are capable of swinging toward and away from one another and are connected together by a spring 32. Fulcrumed on a fixed pivot 33 is a three-armed lever, two arms 33^a, 33^b of which extend in opposite directions and the third arm 33^c of which through a link 34 is connected to an arm of a bell crank lever 21 fulcrumed on a fixed pivot 21^a. The other arm of that bell crank lever 21 constantly engages a cam groove 18^a provided on one of the faces of the gear 18. Through the medium of the bell crank 21 and cam 18^a the lever 33^a, 33^b, 33^c will receive a rocking movement, the direction of which will change with each revolution of the shaft 1.

In the present embodiment of my invention the arms 24, 25 are each formed with two outer notches 24^a, 25^a and one inner notch 24^b, 25^b respectively. Either one of the diametrically opposed arms 33^a, 33^b of the three-armed lever is adapted at times to engage the inner notch of the adjacent member 24 or 25 and while rocking on its pivot 33 operate the slide 23 whereby through the medium of the four-armed lever 20, link 14, lever 13 and rod 12, the toggle mechanism 10 and 11 is operated to bring about the adjustment of the needle actuating rollers 6 and 8, as heretofore stated.

Cooperating with the outer notches of the arms 24, 25 are locking members 26, 27 which are fulcrumed on fixed pivots 26^a, 27^a respectively, and are connected together by a link 26^b. The member 27 is in form of a multiple-armed lever of which one arm with its free end 27^c is adapted at times to engage either one of the outer notches 25^a of the arm 25. Another arm 27^d carries a pin 27^e which at times is adapted to engage the lower end of the arm 25. A third arm 27^f is adapted at times to cooperate with a part 31 to lock the arm 25 in position. A fourth arm 27^g is adapted at times to be acted upon by a rocking arm 22. The member 26 is in form of a two-armed lever, of which one arm with its free end 26^c is adapted at times to engage either one of the outer notches 24^a of the arm 24 and the other arm is connected to the link 26^b by a pin 26^e which at times is adapted to act against the lower end of the arm 24.

The rocking lever 22 is in form of a bell crank lever fulcrumed on a fixed pivot 22^a. One of its arms constantly engages a cam groove 19^a formed on one of the faces of the gear 19, while the other arm of said lever extends downwardly into the path of the lever 31. The latter is fulcrumed on a fixed pivot 31^a and is actuated by a spring 31^b.

Pivoted at 30^a to the upper free end of said lever 31 is a member in form of a plate 30 or the like, which extends on both sides of its pivot and is actuated by a spring 30^b.

28 denotes an electro-magnet which is energized from a suitable source on pressing a button that may be conveniently arranged on the pantograph (the electric source, button and pantograph not being shown). The armature 29 of the electro-magnet is in form of a three-armed lever fulcrumed on a fixed pivot 29^a. One arm 29^b of said lever extends toward the member 30 to constantly rest thereon. The second arm 29^c extends toward the lower end 37^b of the bar 37. The third arm 29^d is adapted to act as the armature proper. The bar 37 which is freely suspended from the arm 20^c of the lever 20 is formed intermediately between its ends with a shoulder 37^e. The bar 37 is capable of adopting three different positions on the manipulation of a hand lever 38. Thus when the latter is in the position *a* as shown, the bar 37 is ineffective, *i. e.* the nose 37^b thereof is removed from the armature and cannot affect the latter. When the hand lever 38 is turned into the position *b*, it will swing the bar against the tension of its spring 37^d toward the armature and cause the nose 37^b to engage the arm 29^c from below (see Fig. 2). When the bar 37 is pulled upwardly through the medium of the slide 23 and the four-armed lever connected with it, it will swing the armature around its pivot 29^a, in the same manner and with the same effect as the armature is swung when attracted by the electro-magnet. When the lever 38 is brought into position *c* it will engage against the shoulder 37^e and lift the bar 37 into the position shown in Fig. 4, in which it will be constantly maintained irrespective of the movements of the slide 23 and the parts connected with it. In that position the bar 37 will hold the armature continuously tilted as when attracted by the electro-magnet. In this tilted position the armature or its arm 29^b will continuously hold the member 30 projected into the path of the rocking lever 22.

Arranged in the vertical path of the arms 24, 25 are catches or stops 35 and 36 respectively which have the object to keep away that one of the two arms 24, 25 which has not been caught by the three-armed lever 33^a, 33^b, 33^c from subsequently becoming caught. For it is clear, if both arms 24, 25 were to be engaged simultaneously by the three armed lever a breakage of the parts would take place.

The function of the different parts of my new controlling mechanism will become clear from the following description of the mode of operation: Ordinarily the hand lever occupies the position *a*. If the operator wishes for some reason to interrupt the

stitching operation, he closes the circuit of the electro-magnet 28 by pressing a button (not shown). The armature 29 is thereupon attracted, swinging on its pivot 29^a, in an 5 anti-clockwise direction. In consequence thereof its arm 29^b depresses one end of the member 30 thereby lifting the opposite end of the latter into the path of the constantly 10 rocking lever 22. When the latter swings from left to right, it encounters the lifted end of the member 30 and presses it to the right, thereby swinging the lever 31 in the same direction against the tension of the spring 31^b. The shoulder 31^c of the lever 31 15 in moving away from underneath the arm 27^c of the member 27 releases the latter. The arms 24, 25 which hitherto have been locked by the members 26, 27 of which the pins 26^c, 27^c have been in engagement with 20 the upper outer notches 24^a and 25^a and the pins 26^e, 27^e with the inner edges of the arms 24, 25 respectively, are now, on the release of the member 27 from the part 31^c of lever 31, unlocked and can follow the tension of 25 their spring 32 swinging inwardly. According to the position of the rocking lever 33^a, 33^b at the time of the unlocking of the arms 24, 25, that one of the latter whose inner notch happens to lie in line 30 with either one of the arms 33^a, 33^b will engage said arm. As the lever continues to rock it will lift the slide 23 which through the medium of the lever 20, bar 14, lever 13 and link 12 collapses the toggle mechanism 35 10 and 11 and thus arrests the needles while the other parts of the machine continue their operation. In this arrested position the needles are shown in Fig. 1. It will be understood that after the electro-magnet 40 has been deenergized, the armature 29 and member 30 by reason of the spring 30^b and the lever 31 by reason of the spring 31^b will swing back into their normal position shown in Fig. 1. Furthermore, the lever 22 during 45 its return stroke from right to left in striking against the arm 27^c of the member 27 returns the latter into its normal or locking position and causes the arm 27^c to re-engage the shoulder 31^c of the lever 31. At 50 the same time the pins 26^e, 27^e again swing the respective arms 24, 25 apart and bring their lower outer notches 24^a, 25^a into engagement with the pins 26^c, 27^c respectively, thereby locking said arms and consequently 55 the slide 23 and toggle mechanism.

When the operator wishes to proceed with the stitching operation he again presses the electric button and the above described operation of the controlling mechanism is repeated, except that the slide 23 now is moved in a downward direction which through the medium of bar 14, lever 13, link 12 straightens out the toggle links 10, 11 whereby the needle rollers 6 and 8 are 60 adjusted into operative position.

If the operator desires to discontinue the operation of the needles for any length of time after every stitch, in order to gain time for the displacement of the tambour frame, he places the hand lever 38 into position *b*, Fig. 3. Hereby the nose 37^b of lever 37 is brought to lie underneath the arm 29^c of the armature. On pressing the electric button after each displacement of the tambour frame, the controlling mechanism 70 will perform the operation above described, moving the slide downwardly and thereby straightening out the toggle links 10, 11. Simultaneously the arm 20^c will swing upwardly and lift the bar 37 by reason of its 80 engagement with the loop 37^a. This will cause the nose 37^b to swing the armature 29 which in the meantime has returned into initial position toward the electro-magnet, in consequence of which the member 30 will 85 once more be brought into the path of arm 22, so that after completion of a stitch the slide 23 will be returned into its lifted position and collapse the toggle mechanism bringing the needles to rest. Thus the 90 needles will be automatically arrested after each stitch and may be maintained in their rest position for any length of time until on pressing the button the controlling mechanism receives a new impulse. 95

If the operator wishes to interrupt stitching operation after every second stroke, he turns the hand lever 38 into position *c*. Thereby the bar 37 is caused to engage with its nose 37^b underneath the arm 29^c of the 100 armature and at the same time is raised swinging the armature toward and into contact with the electro-magnet 28 as shown in Fig. 3. In this position the armature is continuously held as long as the hand lever 105 38 is in *c* position. The member 30 is held thereby continuously in the path of the swinging lever 22 and the controlling mechanism alternately lifts and lowers the slide 23 and straightens and collapses the 110 toggle mechanism. Of course, the same effect would be obtained if the operator were to keep the hand lever always in either of the positions *a* and *b*, and continuously press on the button. But this, of course, 115 would be objectionable as it would not only tire his hand but also hinder him from doing something else.

The above specified structure is only one embodiment of my controlling mechanism, and it is understood that the same may be modified in various ways without deviating from the principle of my invention. I, therefore, do not wish to restrict myself to the details described and shown. 120

What I claim and desire to secure by Letters Patent is:

1. In an embroidering machine, the combination with embroidering implements, of a controlling mechanism including a con- 130

stantly moving member, means which during any stroke of the machine are capable of engaging and have the tendency to engage with said member and means for normally preventing such engagement and which on receiving an impulse will release said first named means and allow of their engagement with said member, whereby they will so affect the said implements as to either render them ineffective or effective without influencing the operation of other parts of the machine.

2. In an embroidering machine, the combination with embroidering implements and their actuating means, of a controlling mechanism including a constantly moving member, means operatively connected to said actuating means and which during any stroke of the machine are capable of engaging and have the tendency to engage with said member and means for normally preventing such engagement and which on receiving an impulse will release the said means and allow of their engagement with said member whereby they will so adjust said actuating means as to render said implements ineffective or effective without influencing the operation of other parts of the machine.

3. In an embroidering machine, the combination with embroidering implements and actuating means therefor including a cam and rollers, of a controlling mechanism including a constantly rocking member, members operatively connected to said rollers and which during any stroke of the machine are capable of engaging and have the tendency to engage with said rocking member and means for normally preventing such engagement and which on receiving an impulse will release said members and allow of their engagement with the said rocking member whereby they will so adjust the rollers relative to the said cam, as to render the said implements ineffective or effective without influencing the operation of other parts of the machine.

4. In a pantograph embroidering machine, the combination with the stitching implements and actuating means therefor, including a cam and rollers co-operating therewith, of a toggle mechanism operatively connected to said rollers and a controlling mechanism operatively connected to said toggle mechanism and which on receiving an impulse will automatically operate the said toggle mechanism so as to adjust said rollers into inoperative or operative position relative to their cam and to correspondingly arrest or start the stitching implements, without affecting the operation of other parts of the machine.

5. In a pantograph embroidering machine, the combination with embroidering implements, of a controlling mechanism

comprising a constantly moving member, a double armed slide operatively connected to said implements and which on receiving an impulse is capable of engaging with said moving member at any stroke of the machine and to render the said implements ineffective or effective without affecting the operation of other parts of the machine and means for starting said mechanism.

6. In a pantograph embroidering machine, the combination with embroidering implements, of a controlling mechanism comprising a constantly moving member, and a device operatively connected to said implements and which on receiving an impulse is capable of engaging said member during any stroke of the machine and to render said implements ineffective or effective without affecting the operation of other parts of the machine, and adjustable means which under the influence of the same impulse will cause the restoration of the implements to their original positions at the next stroke of the machine.

7. In a pantograph embroidering machine, the combination with embroidering implements, of a controlling mechanism comprising a constantly moving member and a slide operatively connected to said implements and which on receiving an impulse is capable of rendering the latter ineffective or effective without affecting the operation of other parts of the machine, and means capable of a series of adjustments and which under the influence of the same impulse according to its adjustment will cause either the restoration of the implements to their original positions at the next stroke of the machine or the continuous alternation of their positions at the succeeding strokes.

8. In a pantograph embroidering machine, the combination with embroidering implements, of a controlling mechanism comprising a constantly moving member and a device operatively connected to said implements and which on receiving an impulse is capable of rendering the latter ineffective or effective without affecting the operation of other parts of the machine, and manually controlled means for starting said mechanism, said mechanism including a member which can be adjusted to influence said means so as to automatically return said implements from ineffective to effective position at the next stroke of the machine.

9. In a pantograph embroidering machine, the combination with embroidering implements, of a controlling mechanism comprising a constantly moving member and a device operatively connected to said implements and which on receiving an impulse is capable of rendering the latter ineffective or effective without affecting the operation of other parts of the machine, and manually

controlled means for starting said mechanism, said mechanism including a member which can be adjusted to influence said means either to automatically return said implements from ineffective to effective position at the next stroke or to continuously maintain said mechanism in motion and thereby alternately render the implements ineffective and effective with each stroke of the machine.

10. In an embroidering machine, the combination with embroidering implements, of a controlling mechanism including a constantly driven rocking lever, movable members operatively connected to said implements and which during any stroke of said rocking lever are capable of engaging and have the tendency to engage with the latter, means for normally preventing such engagement and which on receiving an impulse will release said movable members and allow of their engagement with said rocking lever and constantly driven means for automatically returning said last named means into locking position.

11. In an embroidering machine, the combination with embroidering implements, of a controlling mechanism including a constantly driven rocking lever, movable members operatively connected to said implements and which during any stroke of said rocking lever are capable of engaging and have the tendency to engage with the latter, means for normally preventing such engagement, locking means which on receiving an impulse will be caused to release the latter means and a common constantly driven means for successively moving both said last named means.

12. In an embroidering machine, the combination with embroidering implements, of an implement controlling mechanism, comprising a constantly driven rocking member, movable members capable of engaging with said rocking member during any stroke thereof and constantly tending to engage therewith, and an electrically controlled means for normally preventing such engagement and which on receiving an impulse will release the said members and allow of their engagement with said rocking member.

13. In an embroidering machine, the combination with embroidering implements, of an implement controlling mechanism, comprising a constantly driven rocking member, movable members capable of engagement with said rocking member at any stroke thereof and having the tendency to engage therewith, electrically controlled means capable of engaging with said moving members at the end positions thereof and adapted on receipt of an impulse to release the said members and allow of their engagement with said rocking member and a constantly driven member to reset the said

latter means into locking position at the end of a stroke of said rocking member.

14. In a pantograph embroidering machine, the combination with embroidering implements, of a toggle mechanism operatively connected to said implements and capable of rendering the latter ineffective or effective without affecting the operation of other parts of the machine, a controlling mechanism connected to said toggle mechanism and comprising a constantly moving member and a device, which on receiving an impulse is capable of engaging said moving member during any stroke of the machine, and manually controlled means for starting said controlling mechanism.

15. In a pantograph embroidering machine, the combination with embroidering implements, of a controlling mechanism to render said implements ineffective or effective without affecting the operation of other parts of the machine, said mechanism including a constantly rocking lever, a double armed slide which on receiving an impulse is capable of engaging with said lever during any stroke of the machine, means for locking said slide in disengaged position, and means for unlocking said slide and simultaneously engaging it with said lever.

16. In a pantograph embroidering machine, the combination with embroidering implements, of a controlling mechanism to render said implements ineffective or effective without affecting the operation of other parts of the machine, said mechanism including a constantly rocking lever, a double armed slide which on receiving an impulse is capable of engaging with said lever during any stroke of the machine, means for locking said slide in disengaged position, automatic means for unlocking said slide and simultaneously engaging it with said lever and manually controlled means for starting said last named means.

17. In a pantograph embroidering machine, the combination with stitching implements, of a controlling mechanism to automatically arrest and start said implements without affecting the operation of other parts of the machine, and including a manually adjustable member, which on adjustment in one position will at the next stroke of the machine automatically restart said implements after they have been arrested and in another position will cause the implements to continuously and alternately change from effective to ineffective position and vice versa.

18. In a pantograph embroidering machine, the combination with embroidering implements, of a controlling mechanism for rendering said implements effective or ineffective without affecting the operation of other parts of the machine, said mechanism comprising a constantly rocking lever, a slide

8
operatively connected to said implements and having two members with which said lever is adapted to engage, means for normally holding said members out of the path 5 of said lever and means which on receiving an impulse will release said members and allow of their moving into the path of said lever, said lever being capable of engaging one member at a time during any stroke of 10 the machine.

19. In a pantograph embroidering machine, the combination with embroidering implements, of a controlling mechanism for rendering said implements effective or ineffective without affecting the operation of other parts of the machine, said mechanism including a constantly rocking double-armed lever, a slide operatively connected to said implements and having two movable notched 15 members with which said lever is adapted to engage, means for normally holding said members out of the path of said lever, means which on receiving an impulse will release said members and means for moving said 20 members into the path of said lever, said lever being capable of engaging one mem- 25

ber at a time during any stroke of the machine.

20. In a pantograph embroidering machine, the combination with embroidering implements, of a controlling mechanism for rendering said implements effective or ineffective without affecting the operation of other parts of the machine, said mechanism comprising a constantly rocking lever, a slide operatively connected to said implements and having two movable members with which said lever can engage, means for normally holding said members out of the path of said lever, means which on receiving an impulse will release said members, means for moving said members into the path of said lever and means for preventing the other member from engaging with said lever while one is in engagement therewith. 30 35 40 45

In testimony whereof I affix my signature in presence of two witnesses.

GOTTWALT SIEBER.
